Patented Nov. 15, 1927.

UNITED STATES PATENT OFFICE.

JOHN F. SHAW, OF SOMERSWORTH, NEW HAMPSHIRE, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed April 22, 1927. Serial No. 185,697.

This invention relates to automatically threading shuttles for looms wherein the filling carrier or bobbin in the shuttle is changed from time to time to maintain the supply of filling during weaving.

In the prior patent to Edward S. Stimpson, No. 1,483,492, dated February 12, 1924, there is shown and described an automatically threading shuttle having a longitudinally extending thread passage and a scroll or thread casting device in the thread passage for casting the thread on the occurrence of a loop or overthrow, and in the later patent to Edward S. Stimpson, No. 1,538,224, dated May 19, 1925, the threading block is shown and described as made of cast iron with surfaces finished to not obstruct movement of the thread. The present invention in one of its aspects is a further development of the shuttle shown and described in the Stimpson patents, and is more particularly directed to means for removing fluff, lint or slubs from the filling as it is withdrawn from the shuttle during weaving. Such fluff, lint or slubs if woven into the cloth are liable to present objectionable surface finish and render the cloth imperfect in certain respects, and an important feature of the present invention therefore consists in a slab catcher having a threading eye of smaller dimensions than the interior open portion of the scroll and located between the scroll and the bobbin chamber to intercept such fluff, lint or slubs and prevent them from being drawn with the filling into the shed.

As pointed out in the Stimpson patents above mentioned, the swirling action of the thread as it is withdrawn from the shuttle on the first pick following replenishment, is utilized in connection with the convolutions of the scroll to effect preliminary threading of the shuttle, and in accordance with the present invention, the fluff catcher is provided with a finger which extends laterally and downwardly relative to the longitudinal thread passage, and has an outer surface which conforms substantially to the convolution of the scroll adjacent thereto, with the result that the swirling action of the thread may be directed into the fluff catcher and also into the scroll on preliminary threading of the shuttle.

Where the threading block is formed of

cast iron as described in the Stimpson Patent, No. 1,538,224, above mentioned, it is desirable that the fluff catcher be secured to the cast iron block, and as one means to this end the cast iron block has a recess formed in the part thereof adjacent the bobbin chamber into which the fluff catching block is seated and secured. It is likewise desirable in the use of a fluff catcher such as contemplated by the present invention, that the swirling action of the thread may not meet with any obstruction by the fluff catcher as it swirls from the filling carrier or bobbin in the preliminary threading, and the present invention, therefore, so combines the fluff catcher with the threading block and scroll as to obviate any obstructions in the path of the swirling thread.

The invention and novel features thereof and new combination of parts will best be made clear from the following description and the accompanying drawings of one good form thereof.

In the drawings:

Fig. 1 is a perspective view of an automatically threading shuttle provided with the present invention, certain portions of the shuttle being broken away;

Fig. 2 is an end view of the threading block and fluff catcher, looking frontwardly from the bobbin chamber; and

Fig. 3 is a side elevation of the threading block and fluff catcher removed from the shuttle.

The shuttle 1 may be formed of wood, as usual, and is provided with the bobbin chamber 2 in which is mounted the filling carrier or bobbin 3, as usual. The forward end of the shuttle 1 has a recess 4 in which is mounted the threading block 5 which, except as hereinafter explained, may be substantially the same as either of the threading blocks in the Stimpson patents hereinbefore mentioned. As usual in shuttles of the replenishing type, the shuttle herein shown is also provided with a side delivery eye 6 from which the thread is drawn during weaving.

The threading block 5 may be secured in the recess 4 by the usual transverse bolt which passes through an opening 7 formed in the threading block, and extending longitudinally of the threading block is the thread passage 8.

Extending frontwardly in the thread pas-

sage is the scroll or thread casting device 9 which may be appropriately secured to the block in any approved manner, or substantially as shown in the Stimpson patents here-
5 tofore called to attention.

Between the scroll 9 and the bobbin chamber is the fluff catcher 10 having an eye 11 which is smaller than the passage leading through the scroll, the result being that as
10 the filling or thread α is withdrawn from the filling carrier or bobbin 3, any fluff or slubs, such as β that happen to cling to the filling will be removed therefrom or be obstructed by the small eye of the fluff catcher
15 and will not therefore be withdrawn with the filling into the shed.

In the present instance of the invention, the threading block 5 is provided with a recess 12 formed in the threading block at a
20 point adjacent the bobbin chamber and the fluff catcher 10 as shown comprises a base portion 13 which may be fitted to the recess 12 formed in the block and be secured thereto by any appropriate means, either by
25 brazing or soldering the fluff catcher to the threading block. Extending from the upper portion 14 of the fluff catcher is the laterally and downwardly extending finger 15 which, in connection with the base portion of the block, provides the thread eye 11, and the upper surface of the laterally and downwardly extending finger is substantially of the same curvature as the adjacent portion of the scroll 9, with the result that such
35 finger offers no obstruction to the swirling action of the thread and does not, therefore, in any way interfere with the preliminary threading of the shuttle on its first pick following replenishment.

40 The fluff catcher 10 frontward of the downwardly and laterally extending finger 15 is provided with a part 16 which as shown is brazed at 17 to the adjacent portion of the scroll 9, and such part 16 conforms sub-
45 stantially to the outer contour or convolution of the scroll adjacent thereto. The result of this particular construction, which may be varied within the scope of the present invention, provides a smooth unobstructed sur-
50 face for the swirling of the thread.

In order that the swirling thread may enter the thread eye of the fluff catcher during preliminary threading of the shuttle, an opening or passageway 18 is provided be-
55 tween the end of the downwardly and laterally extending finger 15 and the base portion of the fluff catcher, and since the curvature of the finger conforms substantially to the curve of the adjacent portion of the scroll, the swirling thread will pass down-
60 wardly at the side of the finger 15 and enter the passageway 18 into the small thread eye of the fluff catcher.

Between the downwardly and laterally ex-
65 tending finger 15 of the fluff catcher and the

part 16, the fluff catcher has a thread guide 19 which is adapted to engage the thread should the shuttle not be preliminarily threaded on the first pick following replenishment, so that on the return of the shuttle 70 to the replenishing box the thread will draw over the guide 19.

The rear edge portion of the part 16 of the fluff catcher which forms one of the walls of the thread guide 19 conforms substantially to the convolution of the rear edge portion of the scroll which, when formed as a thread casting device, as in the patent heretofore mentioned, will enable the thread to be thrown from the shuttle on the occurrence of a loop or overthrow.

From the construction described it will be apparent that the present invention provides in connection with the automatically threading shuttle of the Stimpson patents, 85 a fluff catcher having an eye smaller than the interior convolutions of the scroll, to thereby remove fluff, lint and slubs before the thread passes into the scroll during the withdrawal of the thread from the shuttle 90 during weaving, and the laterally and downwardly extending finger 15 which conforms substantially to the exterior contour or convolutions of the adjacent portions of the scroll offers no obstruction to the swirling 95 thread during preliminary threading of the shuttle on the first pick following replenishment.

As hereinbefore mentioned, also, it will be apparent that the fluff catcher 10 may be 100 secured in position between the scroll and bobbin chamber by means suitable for this purpose, but, in order to obviate the formation of any obstruction, such as cracks or projections between the scroll and fluff 105 catcher, it is preferred that the fluff catcher be brazed to the scroll as hereinbefore noted and as indicated at 17, Fig. 1.

What is claimed is:

1. A filling replenishing shuttle having a 110 bobbin chamber and side delivery eye, a threading block between the bobbin chamber and side delivery eye having a longitudinally extending thread passage, a scroll in the thread passage, a fluff catcher having a 115 thread opening smaller than the opening in the scroll and secured to the threading block between the scroll and bobbin chamber and having a laterally and downwardly projecting finger conforming substantially with 120 the curvature of the scroll adjacent thereto for cooperation with the scroll in directing the swirling thread into the fluff catcher and scroll during shuttle threading.

2. A filling replenishing shuttle having a 125 bobbin chamber and side delivery eye, a threading block having a scroll extending frontwardly in the thread passage, a fluff catcher having a thread eye smaller than the opening formed by the convolutions of the 130

scroll and located between the scroll and bobbin chamber said fluff catcher including a base portion and a laterally and downwardly extending finger having an exterior surface conforming substantially with the curvature of the scroll adjacent thereto.

3. A filling replenishing shuttle having a bobbin chamber and side delivery eye, a threading block having a longitudinal thread passage, a scroll extending frontwardly in the thread passage, a fluff catcher between the scroll and bobbin chamber having a finger which extends laterally and downwardly of the thread passage in substantial conformation with the convolution of the scroll and forming a thread eye smaller than the opening through the scroll to catch fluff on the thread as it is withdrawn from the shuttle.

4. A filling replenishing shuttle having a bobbin chamber and side delivery eye, a threading block having a longitudinal thread passage, a scroll extending frontwardly in the thread passage, a fluff catcher between the scroll and bobbin chamber having a finger which extends laterally and downwardly of the thread passage in substantial conformation with the convolution of the scroll and forming a thread eye smaller than the opening through the scroll to catch fluff on the thread as it is withdrawn from the

shuttle, and means for securing the fluff catcher to the threading block.

5. A filling replenishing shuttle having a bobbin chamber and side delivery eye, a 35 threading block having a longitudinal thread passage and provided with a recess adjacent the bobbin chamber, a scroll extending forwardly in the thread passage, a fluff catcher comprising a block seated in the recess of 40 the threading block and formed with a laterally and downwardly extending finger forming a thread eye smaller than the opening of the scroll and having its exterior surface conforming with the adjacent convolution of the scroll. 45

6.-A filling replenishing shuttle having a bobbin chamber and side delivery eye, a cast iron threading block having a longitudinally extending thread passage, a scroll in 50 the thread passage, and a fluff catcher between the scroll and bobbin chamber formed with a thread eye smaller than the opening in the scroll and provided with a side entrance to the eye, and a finger extending laterally and downwardly from the fluff catcher and having its exterior surface in 55 substantial conformity with the adjacent portion of the scroll.

In testimony whereof, I have signed my 60 name to this specification.

JOHN F. SHAW.
